UNITED STATES PATENT OFFICE

111,503

DESIGN FOR A PHYSICIAN'S EQUIPMENT CABINET

Jack Beeber, New York, N. Y.

Application March 10, 1938, Serial No. 75,722

Term of patent 7 years

To all whom it may concern:

Be it known that I, Jack Beeber, a citizen of the United States, residing at New York, in the county of New York and State of New York, have invented a new, original, and ornamental Design for a Physician's Equipment Cabinet, of which the following is a specification, reference being made to the accompanying drawing, forming a part thereof.

The figure is a front perspective view of a physician's equipment cabinet, showing my design.

The characteristic feature of the design resides in providing each of the doors and drawers of the lower portion of the cabinet with a relatively dark central panel surrounded by a streaked border having miter corners, a thin strip of contrasting color being interposed between each said panel and border, all as shown.

I claim:

The ornamental design for a physician's equipment cabinet, substantially as shown and described.

JACK BEEBER.
